UNITED STATES PATENT OFFICE.

JOHN W. HOLZ, OF DETROIT, MICHIGAN.

COMBINATION-LOCK.

1,171,202.

Specification of Letters Patent.

Patented Feb. 8, 1916.

Application filed April 19, 1915. Serial No. 22,255.

To all whom it may concern:

Be it known that I, JOHN W. HOLZ, a citizen of the United States, residing at Detroit, in the county of Wayne and State of Michigan, have invented a new and useful Combination-Lock, of which the following is a specification.

This invention relates to locks provided with notched circular tumblers which may be positioned by means of revoluble knobs or buttons, and its object is to provide a device of this character which shall be strong and easily assembled and which may be cheaply constructed.

This invention consists in the details of construction illustrated in the accompanying drawings and specifically pointed out in the claims.

In the drawings, Figure 1 is an elevation 20 of a case provided with a lock embodying the present invention. Fig. 2 is a rear view of the lock with the cover plate removed. Fig. 3 is a section on the line 3—3 of Fig. 2. Fig. 4 is a section of the tumblers. Fig. 25 is an elevation of one of the tumblers and of the latch. Figs. 6 and 7 are views of two other tumblers. Fig. 8 is an elevation of the latch moved out of engagement with the hasp.

Similar reference characters refer to like parts throughout the several views.

The case or receptacle to which this lock is attached may be of any desired construction and forms no part of this invention. It is desirable that one of the members to be secured together shall be provided with a hasp 1 having a notch 2 to receive a latch, and the other member be adapted to support the body of the lock, which, in the present case, is shown to consist of the end plate 3, cylindrical ring 4, radial flange 5 and cover plate 6. An annular dial plate 7 may be secured to one of the members to be secured together and may have characters 8 of any desired type. Its inner diameter may be just about the same as that of the knob 9, as shown in Fig. 1, or the size may be such that indicating fingers 10 may be mounted on the knob 11 and extend toward the ring 12. A plurality of fingers 10 or arrows 14 (Fig. 1) may be employed to confuse unauthorized persons attempting to operate the lock.

Secured to the knob 11 is a short shaft

15 on which the tumblers 16, 17 and 18 are 55 loosely mounted, separated by washers of any desirable construction, as shown in Figs. 3 and 4. On the end of the shaft 15, opposite the knob, is secured a fourth tumbler 19, provided with a pin 20 that extends 60 through the circular slots 22, 23 and 24 in the tumblers 16, 17 and 18, respectively. The periphery of each tumbler has a deep notch 25 and many small notches or nicks 26. The tumbler 16 is slightly larger than 65 the tumbler 17 adjacent to it; this tumbler 17 is slightly larger than the tumbler 18 next to the latch; and this, in turn, is slightly larger than the tumbler 19 on the end of the 70 shaft 15. By turning the knob and the shaft 15, all the tumblers can be turned to the right (by means of the pin 20) until the tumbler 16 is at the position shown in Fig. 5. The shaft 15 may then be turned to the left until the tumbler 17 is at the position 75 shown in Fig. 6; then to the right until the tumbler 18 is in the position shown in Fig. 7; and then to the left until the tumbler 19 is in the position shown in Fig. 2. After 80 tumbler 16 has been positioned, the pin 20 moves in its long slot 22 to position the tumbler 17. After that, the pin 20 moves in the slots in the tumblers 16 and 17 to position the tumbler 18. And after this tumbler is positioned, the pin 20 moves in the slots of 85 all three slotted tumblers until the tumbler 19 is in proper position, that is, with the notches 25 of all the tumblers in alinement.

Mounted on the shaft 15 is a latch consisting of a plate 27 having a lip 28 at one end 90 adapted to engage in the notch 2, and an oppositely extending pin 29 at the other on which is mounted a pawl 30 having a lip 31 adapted to engage all the tumblers. A post 32 mounted on the plate 3 carries one 95 end of the tension spring 33 and the other end of the spring connects to the lip 31 of the pawl 30. A small lug 35 projects from the plate 3 about the same height as the thickness of the pawl 30 which may engage 100 therewith.

When the tumblers have been positioned as shown in the drawings, the shaft 15 may be turned to the left, and the end tumbler 19, by reason of the lip 31 of the pawl 30 extending 105 into its deep notch 25, will pull the pawl around with it to the left and carry the latch lip 28 on the plate 27 out of the notch 2 in

the hasp 1, as shown in Fig. 8. This movement will slide the pawl 30 up along the lug 35 and move the lip 31 radially outward out of the deep notches 25 in all the tumblers 5 until finally this lip will escape from the notches, as shown in dotted lines in Fig. 5, permitting the tumblers to freely revolve underneath this lip and permit the latch to be swung back to normal position, which is the 10 solid line position of the latch and dotted line position of the pawl in Fig. 5.

As all the tumblers are formed with nicks 26, the same clicking will be heard and felt at all times, no matter which tumbler is engaged by the lip 31 of the pawl. Thus the click of the pawl dropping from one tumbler to the other is indistinguishable. By changing the relative positions of the notches 25 and the circular slots in the tumblers 16, 20 17 and 18, and the relative positions of the pin 20 and notch 25 of the tumbler 19, the "combination" of the lock may be varied. This may even be done by omitting or turning over any one or more of the slotted 25 tumblers.

It will be noted that a single spring holds both the pawl and latch in operative position and that the tumblers can be moved in either direction to carry them to "locking" 30 position. The extreme simplicity of this construction prevents it getting out of order.

By reason of the latch plate being bent down (Fig. 3) to permit the pawl 30 to lie between it and the plate 3 of the lock case, 35 this pawl will always be guided for proper movement and be prevented from tilting. The lug 35 may be so secured to the plate 3 that there is no possibility of its getting loose, but in the event this should occur, it 40 will be prevented from moving out by that portion of the latch plate 27 that extends over it. This lug forces the pawl out of engagement with the tumblers when the latch is swung around beyond a certain pre- 45 determined distance and all of the tumblers may then revolve freely, the engagement of the lip 31 with their peripheries occurring immediately by reason of the spring 33 pulling the latch plate back to normal position.

50 The details and proportions of construction of this lock may all be varied without departing from the spirit of my invention as set forth in the claims.

I claim:—

55 1. In a combination lock, a lock body, a shaft revoluble therein, a tumbler loosely mounted on the shaft and having a notch in its periphery and a segmental slot, a tumbler secured to the shaft and having a 60 notch in its periphery, a pin extending from said second tumbler through the slot in the first, a latch plate pivotally mounted on the shaft, a pawl mounted on the plate and having a lip in engagement with said 65 tumblers and adapted to enter said notches,

a hasp to be engaged by the latch and a spring engaging the pawl to hold it against the tumblers and to hold the latch in engagement with the hasp.

2. In a combination lock, a lock body, a shaft revoluble therein, a tumbler loosely mounted on the shaft and having a notch in its periphery and a segmental slot, a tumbler secured to the shaft and having a notch in its periphery, a pin extending from 70 said second tumbler through the slot in the first, a latch plate pivotally mounted on the shaft, a pawl mounted on the plate and having a lip in engagement with said tumblers and adapted to enter said notches, a hasp to be engaged by the latch, and a lug 75 secured to the lock body to swing the pawl out of the notches when the latch is swung a sufficient distance.

3. In a combination lock, a lock body, a shaft revoluble therein, a knob for turning the shaft, a plurality of tumblers loosely mounted on the shaft and each having a notch in its periphery and a segmental slot, a tumbler secured to the shaft and having a notch in its periphery and a pin extending 80 into the slots in the other tumblers, a latch plate pivotally mounted on the shaft, a pawl pivoted to said plate, a spring to hold the pawl against the peripheries of 85 the tumblers, and a hasp adapted to be engaged by said latch plate under tension 90 of said spring.

4. In a combination lock, a body, a shaft revolvably mounted therein, a plurality of tumblers on the shaft and each having a notch in its periphery, a latch plate pivotally mounted on the shaft, a hasp adapted to be engaged by the latch, a pawl mounted 100 on the latch plate and adapted to enter 105 said notches, a spring to hold the latch plate in hasp-engaging position and the pawl in engagement with the tumblers, and stationary means engaged by the pawl whereby it 110 may be forced out of the notches in the tumblers when the latch plate is moved out of hasp-engaging position.

5. In a combination lock, a lock body, a shaft revoluble therein, a tumbler loosely mounted on the shaft and having a notch in its periphery and a segmental slot, a tumbler secured to the shaft and having a notch in its periphery, a latch plate pivotally mounted on the shaft, a pawl mounted on 115 the plate and having a lip in engagement with said tumblers and adapted to enter said notches, a hasp to be engaged by the latch, and a stationary lug on the lock body with which the pawl engages and whereby 120 its lip is forced out of said notches.

6. In a combination lock, a body, a shaft revolvably mounted therein, a plurality of tumblers on the shaft, each having a notch in its periphery, a plate pivotally mounted 125 on the shaft, a pawl mounted on the plate 130

and adapted to enter said notches, a spring to hold the pawl in engagement with the tumblers, and stationary means engaged by the pawl whereby it may be forced out of the notches in the tumblers when the plate is swung in one direction about the shaft.

5 In testimony whereof I sign this specifica-

tion in the presence of two subscribing witnesses.

JOHN W. HOLZ.
